UNITED STATES PATENT OFFICE.

FRANK W. ADSIT, OF MINNEAPOLIS, MINNESOTA.

INTERCOMMUNICATING LOCKOUT TELEPHONE SYSTEM.

1,228,634.

Specification of Letters Patent.

Patented June 5, 1917.

Application filed May 24, 1915, Serial No. 30,166. Renewed February 18, 1917. Serial No. 148,901.

To all whom it may concern:

Be it known that I, FRANK W. ADSIT, a citizen of the United States, residing at Minneapolis, in the county of Hennepin, 5 State of Minnesota, have invented new and useful Improvements in Intercommunicating Lockout Telephone Systems, of which the following is a specification.

My invention relates more particularly to 10 providing means whereby one subscriber on a telephone party line may call any other subscriber on that line at will, and also provides means whereby the conversation between the two parties is private, the remaining 15 parties on the line being locked out, and provides further means whereby the system may be automatically restored to normal without action on the part of the subscriber other than hanging his receiver on the 20 switch-hook.

The drawing discloses three magneto type 25 of telephones equipped with my invention and denoted by the letters A, B and C. The circuits at the three stations are identical and for convenient reference the wires and 30 parts of station A are numbered, and corresponding elements at B and C are denoted by the same numbers where referred to in this specification with the symbol (') added at station B and the symbol (") added at station C.

The arrangement of circuits and apparatus in my invention is such that it may be embodied in the form of an attachment that 35 can be added to the common type of magneto telephone and does not necessarily mean a complete instrument including the ordinary telephone apparatus.

The three subscribers' sets, A, B and C 40 disclosed in the drawing are connected to the metallic line denoted by numerals 1, and 2 and there is further provided a ground connection 3, 3', 3'' which may be a connection to the earth or a third wire may be 45 used and the earth connection dispensed with.

If party A wishes to talk with party B, he will first set the dial 4 to correspond with the number of the telephone of subscriber 50 B and then turn the crank of the magneto 5, which is adapted to supply alternating current, the result being then a flow of alternating current from the magneto 5 as follows:

55 Wires 6 and 7 to shaft 8, contact 9, wire 10, coil 11, wires 12 and 13 to the line wire

2, wire 14, to the other side of the magneto 5. The alternating current flowing through the coil 11 pulls the armature 15 downward, freeing the catch 16 and operating the bank 60 of springs associated therewith. The continuation of the act of turning the magneto crank now sends current through wire 17, contact 18, wire 19, contact 20, wires 21 and 22, to the line wire 1, and the other side of 65 the magneto 5 being connected by wire 14 to the side 2 of the line, magneto current is supplied to whatever apparatus is then bridged to these wires at any instrument on the line.

70 Continuing with the circuit at A, the coils 23 are connected to the line wire 2 by wires 13, 12, 93 and 24, and to the line wire 1 by wires 25, 26, 27 and 22, hence this coil will be actuated by the alternating current 75 from the magneto 5 and by means of the actuating pawl 28 and retaining pawl 29 will turn the ratchet wheel 30 in a clockwise direction.

As coils 23' and 23'' are connected similarly to the line wires 1 and 2, the ratchet wheels 30' and 30'' will be operated in a similar manner.

As the ratchet wheels 30, 30' and 30'' are all stepped around by the alternating current 85 from a common source, namely the magneto 5, their motion will be synchronous.

The shafts 8, 8' and 8'', which are driven by the ratchet wheels 30, 30' and 30'' respectively, carry contact pointers 31, 31' and 31'' respectively, which are insulated from their shafts by the bushings 32, 32' and 32'' respectively.

These respective contact pointers are 95 adapted to make contact with the springs 33, 33' and 33'' respectively, as they are rotated, and the angular position of the pointers 31, 31' and 31'' is in each case determined by the number given to that particular telephone, the adjustment being made by means of the screws 34, 34' and 34'' respectively and each of the pointers will therefore make its contact with its respective spring at a different time in the turning 105 of the synchronously moving wheels 30, 30' and 30''.

As the positioning of the pointers 31, 31' and 31'' correspond to the number of the telephone in each instance, when the dial 4 110 at station A is set to correspond to subscriber B, the contact spring 35, has been

by this act positioned so that the pointer 36 at station A will make contact with the spring 35 at the same time that contact pointer 31' makes contact with the spring 33' at station B.

The contact pointers 36, 36' and 36'' are insulated from the shafts 8, 8' and 8'' respectively by the bushings 37, 37' and 37'' respectively.

10. When the pointer 36 at station A makes contact with the spring 35, and the pointer 31' at station B makes contact with the spring 33', a circuit for the magneto current is established as follows:

15. Magneto 5, wire 14, line wire 2, wires 13', 39', coil 40', wire 41', contact 42', wire 43', spring 33', contact pointer 31', spring 44', wires 45', 46', ground 3', through the ground to the ground at 3 at station A, wires 46, 47, 20 spring 48, contact pointer 36, spring 35, spring 49, wires 50, 26, 27, 21, contact 20, wire 19, contact 18, wire 17, contact 51 which is closed by the act of turning the magneto crank, as in common types of magneto, to the other side of the magneto 5.

25. The magneto current passing through the coil 40' pulls up the armature 52' releasing the latch 89' and operates the bank of springs associated therewith. The crank of the magneto 5 still turning, the ratchet wheels 30, 30' and 30'' are still stepping synchronously until the stops 53, 53' and 53'' make contact with the contact points 54, 54' and 54'', respectively, which stops further rotation of the wheels and also establishes a circuit as follows:

30. Magneto 5, wires 6 and 7, shaft 8, stop 53, contact point 54, wire 55, contact 96, wire 41, coil 40, wires 39, 13, line wire 2, wire 14, 40 to the other side of the magneto 5, operating the armature 52 releasing the latch 89, and through this the bank of springs associated therewith.

45. This final operation of the bank of springs associated with coil 40 establishes a circuit as follows:

50. Magneto 5, wires 6, 56, contact 57, wires 58, 59, switch hook contact 60, ringer 61 to the ground at 3, through the ground to the ground at 3' at station B, ringer 61', switch hook contact 60', wires 59', 58', contact 57', wires 56', 6', contact 38', (which short-circuits the magneto winding when the crank is not being turned), wire 14' line wire 2, 55 wire 14 to the other side of the magneto 5, thus ringing both ringers 61 and 61' in series over the line wire 2 and through the ground.

60. As both bells are rung in series, when the party B answers by removing the receiver 62' from the switch hook 63', the circuit is opened at the contact 60', and both ringers will be stopped from ringing; hence the party at A will know the party at B has answered, and will then remove his own re-

ceiver 62 from switch hook 63, and the two parties will talk, the talking circuit being as follows:

70. The primary circuit in the talking set is similar in each instrument and is indicated at the station A as follows:

Battery 64, wire 69, primary 68 of the induction coil, transmitter 66, wire 65, contact 70, switch hook 63, wires 59, 94 to the other side of battery 64.

75. The secondary circuit at station A is as follows: secondary 71 of the induction coil, wire 72 to line wire 1; from the other side of the secondary 71 of the induction coil, wire 73, condenser 74, wire 75, receiver 62, wire 76, contact 77, switch hook 63, wires 59, 58, contact 57, wires 56, 6, contact 38 (which now short-circuits the winding of the magneto 5 as the crank is no longer being turned), wire 14 to the other side 2 of the line.

80. The secondary circuit of station B is identical, and the connection of the two circuits by the line wires 1 and 2 completes the talking circuit.

85. Referring now to circuit "C", the only operation that has taken place has been the stepping of the wheel 30'' synchronously with the wheels 30 and 30', but, as the contacts between pointer 31'' and spring 33'' were made at a time when no contact was made by contact pointer 36 and spring 35 at station A, no coils received operating current except the coils 23'' which are permanently bridged on the line wires 1 and 2, and 90 serve to step around the wheel 30''.

95. As the secondary of the talking set at station C terminates at the contact 57'' which is open as the coil 40'' has not been operated, that telephone is locked out, and a party at that station cannot hear any conversation going on over the line wires 1 and 2, nor can he, by talking into his transmitter, send any voice currents out on to that line.

100. Furthermore, the magneto circuit from contact 51'', wire 17'', contact 18'', wire 19'', is open at contact 20'' and the magneto circuit from wire 6'', wire 56'' is opened at 57'', and also from wires 6'', 7'', shaft 8'' is open until stop 53'' makes contact with 54''. Thereafter as the circuit through wire 55'' is open at contact 96'' the subscriber's generator at station C is also inoperative.

110. The description heretofore, together with the drawings, indicate that it is necessary to have the contact at 9, 9' or 9'' closed in order to secure control of the line, and as all of the ratchet wheels are stepped synchronously, the first step will break this contact in all instruments, but, at the station initiating the call, control of the line is given to that party through the operation of the bank of springs associated with the coil 11.

The system is restored to normal by bridging direct current of a proper polarity across the line wires 1 and 2, the current at station A flowing through the coil 23, which is permanently bridged on the line and whose action is polarized by the permanent magnet 97 in such direction that the contact 79 is closed, which places the coil 80 across the line wires 1 and 2, the circuit 10 being from line 1, wires 22, 27, 81, coil 80, wire 82, contact 79 wires 83, 93, 12, 13, to the other side 2 of the line. The direct current which then flows through coil 80, pulls the armature 84 which is pivoted at 85 toward the coil 80, one end of this lever lifting out the actuating pawl 28 and the retaining pawl 29, the other end of the lever through the insulating bar 94 moving the main springs 95 and 86 back to their normal 15 position and allowing the armature 15 to be retracted to its normal position by the spring 87; also through the means of the insulating bar 88 the main springs 89 and 90 are restored to their normal positions, 20 allowing the armature 52 to be retracted by spring 91.

The action at stations B and C is the same and thus the bridging of direct battery of suitable voltage on the line wires 1 and 2, 30 through any means, automatic or manual, serves to restore the system to its normal condition in readiness for another call.

The operation in practice is simple, positive and efficient. It is only necessary for 35 the subscriber to set his dial to the number of the party desired and turn the magneto-crank until his own bell rings, when he knows the other party's bell is being rung, and continue his ringing until he knows, 40 through the stopping of the ringing of his own bell that the other party has answered.

In a system using fifteen stations on a line, the entire act of selection up to the time when the called party's bell begins 45 ringing, will not normally exceed three to four seconds.

While I have described and illustrated my invention with one particular circuit and arrangement of apparatus, I wish it 50 understood that I do not confine myself to this particular arrangement of parts and circuit as described, as it is evident my invention may be applied in various manners within the scope of the following claims:

55 1. In an intercommunicating telephone lock-out system the combination of two subscribers' stations, a pair of wires connecting said subscribers' stations, a ground connection at each of said subscribers' stations, 60 means at each of said subscribers' stations adapted to generate alternating current, means responsive to said alternating current at each subscriber's station, a shaft at each subscriber's station adapted to be rotated by 65 said means responsive to said alternating

current, a contact positioned near said shaft, means associated with said shaft adapted to close and open said contact during the rotation of said shaft, a second contact positioned near said shaft, a second means associated with said shaft adapted to close and open said second contact during the rotation of said shaft, and adjustable means adapted to vary the point in the rotation of said shaft at which said second contact is closed 70 and opened. 75

2. In an intercommunicating telephone lock-out system the combination of two subscribers' stations, a pair of wires connecting said subscribers' stations, and the combination at each of said subscribers' stations of an alternating current generator, a shaft, means responsive to alternating current adapted to rotate said shaft, a permanently located contact point adjacent to said shaft, 80 a contact maker on said shaft adapted to make contact with said permanently located contact point during the rotation of said shaft, a settable contact point positioned adjacent to said shaft, and a second contact 85 maker on said shaft adapted to make contact with said settable contact point during the rotation of said shaft.

3. In an intercommunicating telephone lock-out system the combination of two subscribers' stations, a pair of wires connecting said subscribers' stations, the combination at each of said subscribers' stations of an alternating current generator, a shaft, means responsive to alternating current adapted 95 to rotate said shaft, a permanently located contact point adjacent to said shaft, a contact maker associated with said shaft and adapted to make and break contact with said permanently located contact point during 100 the rotation of said shaft, a settable contact point positioned adjacent to said shaft, a second contact maker associated with said shaft adapted to make and break contact with said settable contact point during the 105 rotation of said shaft, means adapted to limit the amount of rotation of said shaft, and a contact adapted to be closed when the rotation of said shaft is substantially completed. 110

4. In an intercommunicating telephone lock-out system the combination of two subscribers' stations, a pair of wires connecting said subscribers' stations, and the combination at each of said subscribers' stations of 120 an alternating current generator, a shaft, means responsive to alternating current adapted to rotate said shaft, a permanently located contact point adjacent to said shaft, a contact maker associated with said shaft 125 and adapted to make and break contact with said contact point during the rotation of said shaft, a settable contact point adjacent to said shaft, a second contact maker associated with said shaft adapted to make contact 130

with said settable contact point during the rotation of said shaft, and a normal contact adapted to be opened at the beginning of the rotation of said shaft.

5. In an intercommunicating telephone lock-out system the combination of three subscribers' stations, a pair of wires connecting said subscribers' stations, and the combination at each of said subscribers' stations of an alternating current generator, a shaft, means responsive to alternating current adapted to rotate said shaft, a permanently located contact point adjacent to said shaft, a contact maker associated with said shaft adapted to make contact with said permanently located contact point during the rotation of said shaft, a settable contact point positioned adjacent to said shaft, a second contact maker associated with said shaft adapted to make contact with said settable contact point during the rotation of said shaft, a normal contact included in the circuit of said subscribers' stations so as to open said circuit when said normal contact is opened, means associated with said shaft for opening said normal contact at the beginning of the rotation of said shaft, electro-magnetic means operable through said permanently located contact point at one of said subscribers' stations when it is being called, by alternating current from said alternating current generator of one of the

other of said subscribers' stations when it is calling through said settable contact at said subscriber's station that is calling. 35

6. In an intercommunicating telephone lock-out system the combination of three subscribers' stations, a pair of wires connecting said subscribers' stations, a ground connection at each of said subscribers' stations, an alternating current generator, a shaft, means responsive to alternating current adapted to rotate said shaft, a permanently located contact point adjacent to said shaft, a contact maker associated with said shaft adapted to make contact with said permanently located contact point during the rotation of said shaft, a settable contact point adjacent to said shaft, a second contact maker associated with said shaft adapted to make contact with said settable contact point during the rotation of said shaft, a normally closed contact adapted to be opened at the beginning of the rotation of said shaft, electro-magnetic means operable by alternating current, whereby the alternating current from said generator may be switched from a circuit including said pair of wires connecting said subscribers' stations to a circuit including one of said wires connecting 40 45 50 55 60 said subscribers' stations and a ground connection.
